FIG. 5.

Inventor:
Orville E. Cook.

by Robert Robert Cook
his attys

UNITED STATES PATENT OFFICE.

ORVILLE E. COOK, OF TROY, NEW YORK, ASSIGNOR TO CLUETT, PEABODY & CO., INC.,
OF TROY, NEW YORK, A CORPORATION OF NEW YORK.

PRESS.

Application filed October 21, 1921. Serial No. 509,321.

To all whom it may concern:

Be it known that I, ORVILLE E. COOK, a citizen of the United States, and resident of Troy, in the county of Rensselaer and State of New York, have invented new and useful Improvements in Presses, of which the following is a specification.

This invention concerns presses of that type wherein the material operated upon is subjected to heat during the pressing operation and relates more particularly to mechanisms of this general character such as are employed for folding and pressing collar and cuff blanks.

When a presser element, as for example the bed plate, of such a machine is electrically heated, a considerable degree of care on the part of the operator is necessary in order to avoid overheating of the machine, particularly during intervals of idleness. The object of the present invention is to provide automatically acting means for controlling the supply of heat to the machine whereby overheating of the presser element or elements may be avoided at all times, whether or not the machine is being operated.

As one mode of attaining this object, a switch may be provided in the heating circuit, such switch being operably connected to one of the work clamping or pressing elements, as for example the die plate whereby movement of the latter to and from operative position serves to close or open the switch. The closing of the switch may serve to initiate the flow of current through the heating coil, but preferably is so arranged as to short circuit a reactance or resistance coil in such circuit through which a predetermined amount of current is constantly passed to the heating coil. With this latter arrangement, the reactance may be so calculated as to provide the precise amount of heat at the presser element necessary to bring the latter to the working temperature and to overcome radiation losses. The short circuiting of the reactance during the operation of the die plate may then serve to supply the additional heat necessary to replace that carried away by the material at each operation. In this way, heat supplied in excess of that necessary to maintain the normal working temperature of the presser is

proportional to the speed of operation of the machine and to the heat consumed at each operation. Thus, overheating of the machine is substantially avoided while no especial care upon the part of the operator is required in maintaining the desired working temperature.

The folding and pressing mechanism disclosed in the patent to Brown 1,053,477, Feb. 18, 1913, lends itself particularly well to the application of the present invention. In the patented mechanism the movable work engaging element is pneumatically actuated, the admission and exhaust of air from the pneumatic cylinder being under control of a manually actuatable valve. In applying the present invention to such an apparatus, it is necessary merely to provide a pneumatic motor for opening and closing the switch above referred to and to connect such motor with the feed pipe of the actuating cylinder for the die plate. As thus arranged the die plate and switch necessarily operate in synchronism.

While as above stated, advantage may well be taken of the presence of operating mechanism such as disclosed in the above patent for securing synchronism of operation of the die plate and switch, it is clearly apparent that electrical or mechanical connections might readily be devised whereby to secure the simultaneous actuation of said parts and it is contemplated that such arrangements may be utilized as circumstances might make expedient.

In the accompanying drawings there is illustrated an arrangement of parts well exemplifying means whereby the above object may be attained, and in such drawings,—

Fig. 1 is a transverse vertical section through a folding and pressing machine of usual type, illustrating the device of the present invention as applied thereto;

Fig. 2 is a cross section to larger scale illustrating the device of the present invention as removed from the machine, such section being taken on a line such as *a*—*b* of Fig. 1;

Fig. 3 is a cross section of the device of Fig. 2 on the line *c*—*d* thereof;

Fig. 4 is a diagrammatic view illustrating

the arrangement of the electric connections;

Fig. 5 is a fragmentary elevation to smaller scale illustrating the device of Fig. 2, the rear cover member thereof being re-
5 moved; and

Fig. 6 is a view similar to Fig. 3 but illustrating a modification.

The machine to which the present invention is shown as applied is of the general 10 type more fully illustrated and described in the aforementioned patent to Brown, to which patent reference may be had for a fuller disclosure of the details thereof. As herein illustrated the machine comprises a 15 frame having legs 1, adjacent legs being united by means of transverse bars such as 2. The machine comprises cooperating work clamping elements of which one is constituted by the usual bed plate 3 having an 20 upper surface of heat conducting material upon which the blank rests during the pressing operation. This bed plate as herein disclosed is provided with chambers 4 in which are located electrically energized heating 25 coils 5. These coils may be of any usual type and are provided with terminals 6, 6^a below the bed plate. During the operation, the work is clamped between the bed plate 3 and the die plate 7 carried upon the end of 30 the lever arm 8. The lever arm 8 is pivoted at the point 9 upon a bracket 10 fixed to the machine frame. A depending arm 11 is fixedly secured to the lever arm 8, being integral therewith, if desired. To the lower 35 end of such arm is connected a spring 12 whose opposite extremity is secured at 13 to the machine frame. The action of this spring is such as normally to retain the die plate 7 in elevated position as indicated in 40 Fig. 1. For depressing the member 7 into operative position whereby to press material against the bed plate 3, a piston 14 is provided, such piston sliding in a cylinder 15 to which air or other pressure fluid may 45 be admitted through a pipe 16. A pipe 17 connects the pipe 16 with a valve box 18 having therein a rotary valve whose stem is indicated at 19. This valve may be of the type shown in the above noted patent, 50 to which reference may be had for the details thereof.

Secured to the valve stem 19 is an arm 20, to the outer extremity of which is pivotally secured the connecting rod 21. The lower 55 end of the rod 21 is connected at 22 to the rear end of a treadle lever 23. The treadle lever is pivoted at 24 to a bracket 25 secured to the frame of the machine and is provided at its forward extremity with a foot 60 engaging portion 26. A spring 27 is secured at 28 to the upper portion of the connecting rod 21 and is attached at its lower end 29 to the frame. The spring as thus arranged tends to hold the treadle lever in the position indicated in Fig. 1. The pipe 30 admits

pressure fluid to the valve box 18 and the valve is so constructed that upon depression of the treadle member 26 by the foot of the operator air is admitted through the pipes 17 and 16 to the cylinder 15, thus causing 70 the piston 14 to act against the arm 11, thereby swinging the lever arm 8 in a clockwise direction and bringing the die plate 7 into operative position of cooperation with the bed plate.

Referring to Figs. 2 and 3, there is indicated a support 31 in the form of a box or hollow casing, such casing being provided with one or more hook members 32 whereby it may be suspended from one of the transverse bars 2 of the frame. Within this casing are arranged a pair of similar resistance or reactance coils 33, such coils being formed upon suitably laminated cores 34. Secured within the casing is an insulating 80 block 35 having mounted thereon a pair of spaced resilient arms 36, each of such arms being furnished at its free extremity with a contact shoe 37. A second block 38 is secured to the face of said first 90 block and to such block are attached a pair of resilient arms 39, such arms having contact shoes 40 at their free extremities. The shoes 37, 40 as thus arranged constitute two pairs of cooperable contact elements. One 95 terminal 41 of one of the coils 33 is connected to a binding post 42 electrically connected to one of the arms 36, while the other terminal 43 of such coil is connected to a binding post 44 which is electrically 100 connected to the corresponding arm 39. In the same manner the terminal 45 of the other coil 33 is secured to the binding post 46 electrically connected to the other of the arms 36, while the other terminal 47 of such 105 coil is secured to the binding post 48, electrically connected to the opposed arm 39. From the posts 42, 46 conductor wires 42^a, 46^a lead to the terminals 6, 6^a of the respective heater coils, while from the posts 11 44, 48 extend conductor wires 61, 61^a leading to any convenient source of electrical energy. The other terminals (not shown) of the heater coils are directly connected to conductors such as 60, also leading to such 11 source of energy.

The opposite wall of the casing from that having the hooks 32 may be removable if desired and to such wall is secured a cylinder 49, such cylinder being provided with a 12 flange 50 which bears against the side wall of the casing, the flange being provided with openings through which pass bolts 51 by means of which the flange is secured to the casing. Within the cylinder is a piston 52 12 provided with a suitable packing 53 and having a piston rod 54 which extends through an opening at 56 in the side wall of the casing.

A coil spring 57 encircles the piston rod, 13

bearing at one end against the piston and at the other against the outer surface of the casing, this spring normally acting to retain the piston in the outer end of the cylinder.

5 A pipe 58 enters the outer end of the cylinder and is arranged for connection to the pipe 16 above referred to, whereby pressure fluid may be admitted from the pipe 16 into the cylinder 49. Secured to the inner end of

10 the piston and within the casing is a transverse block 59, which extends to points behind the respective arms 39 and is adapted to contact simultaneously with such arms upon movement of the piston inwardly to-

15 ward the casing.

In Fig. 4 there is indicated diagrammatically a wiring arrangement whereby one of the heating coils 5 is connected in circuit with its reactance coil 33 and the corresponding switch comprising the contact

20 shoes 37, 40.

With the parts as indicated in Fig. 1, current flowing through the wire 61 passes through the reactance coil 33, wires 41 and 25 42^a, thence through the heating coil 5, and to the return wire 60. The reactance coil 33 is of such dimensions that the current permitted to pass through the coil 5 is just sufficient to heat the bed plate 3 to the desired 30 working temperature and to maintain it at such temperature so long as the machine is not in operation. When, however, the die plate 7 is brought down upon work placed upon the bed plate in the manner previously 35 described, pressure fluid from the pipe 16 is admitted through the pipe 58 to the cylinder 49. The piston 52 is thus actuated to carry the block 59 into contact with the arms 39. This brings the blocks 40 into contact with 40 the shoes 37, thereby short circuiting or shunting the reactance coil 33. This permits current in greater quantity to pass through the coil 5 whereby the heat imparted to the bed plate is substantially increased. This 45 increase in heat is sufficient to make up for that carried away at each operation by the material operated upon. The current is thus permitted to flow in augmented quantity during the pressing operation but immediately upon release of the treadle member, the 50 pressure is exhausted from the pipe 16 and simultaneously from the cylinder 49. The spring 57 immediately retracts the piston 52, carrying the contact member 40 away from 55 the member 37, thus again cutting in the reactance coil 33 thereby reducing the current through the heating coil to the normal amount. With this arrangement it is evident that there is little probability of over- 60 heating of the machine, the normal heat supplied being merely sufficient to overcome radiation losses. It is also clear that the increased amount of heat necessary to make up for that absorbed by the material is only 65 supplied during the pressing operation and

is entirely dependent upon the movement of the die plate 7 into operating position. Such surplus heat, therefore, is supplied in direct ratio to the duration of each pressing operation, and as successive operations normally consume substantially equal amounts of time, the added heat thus supplied is substantially proportional to the speed of operation of the machine so that carelessness or inattention on the part of the operator is of little consequence, so far as the matter of overheating of the parts is concerned.

While the device hereinabove described comprises duplicate heating coils in the bed plate and duplicate switches and reactance coils, it is to be understood that a greater or lesser number of such devices might well be employed if occasion should so require. It is also to be understood that while the coil 33 has been referred to as a reactance coil, a resistance coil might be substituted therefor if direct current were to be employed for the heating coil. It is also evident that while the arm 8 and the switch closing block 59 have been shown as simultaneously operable by pneumatic means, other pressure fluid might be employed for actuating them and that so far as the broader aspects of the invention are concerned, such elements might be simultaneously actuated by mechanical or electrical means.

One mode of actuating the switch mechanically is indicated in Fig. 6 wherein the casing 70 is provided with the attaching hook 71 and has mounted within it the insulating blocks 72, 73. Carried by these blocks are the resilient arms 74, 75 provided with the contact shoes 76, 77, respectively. Passing through an opening 77^a in the front wall of the box or casing 70 is a lever 78, such lever being pivoted at 79 between a pair of ears 80, one only of such ears being shown. This lever extends into the casing and is bent at 81 and again at 81^a whereby to provide the portion 82 which extends substantially parallel to the wall of the casing. Mounted upon the end of the member 82 is the transverse block 83 positioned adjacent to the arms 75. The upper end of the lever 78 may be connected by 115 links or in any other desirable and convenient manner to the lever arm 8 or to the depending portion 11 thereof, as may be found most convenient, the connections being such that upon depression of the die plate 7, the member 82 will be swung laterally, thereby moving the shoes 77 into contact with the shoes 76. The operation of the device in controlling the current through the heating coil will thus be substantially like that previously described.

It is contemplated that while the invention herein shown has been illustrated as applied to a folding and pressing machine for use in the manufacture of collars and cuffs,

certain of its broader aspects might well be embodied in presses of other types wherein heated presser elements are employed.

I claim:

5. 1. A machine for folding and pressing collar and cuff blanks having presser mechanism comprising a presser element having a heat conducting blank engaging surface, means whereby said element may be heated, 10 means for actuating said mechanism, and means operating in synchronism with said actuating mechanism for controlling the heat supplied to said presser element.

15. 2. A machine for folding and pressing collar and cuff blanks comprising presser means having a heat conducting blank engaging surface, a heater associated therewith, means for producing pressure between the blank engaging surface and a blank, an 20 actuator for said pressure producing means, and means for synchronously controlling said actuator and said heater so that the heat supplied to said heat conducting surface is proportional to the time during 25 which the blank is subjected to pressure against said heated surface.

30. 3. A machine for folding and pressing collar and cuff blanks comprising relatively movable and cooperable heat conducting elements between which the material may be clamped, actuating means for one of said elements, heating means for the other of said elements, and connections between said actuating and heating means constructed 35 and arranged to determine the heat supplied by the latter in direct ratio to the period of time during which the material is clamped between said elements.

40. 4. A machine of the class described comprising a bed plate constituting a work clamping element, a cooperating work clamping element movable toward and from said bed plate, means for supplying heat to said bed plate, means for controlling the 45 heat supplied by said heating means, and connections between said movable clamping element and said heat controlling means so constructed and arranged as to increase the supply of heat as the said movable element 50 is moved toward the bed plate.

55. 5. A pressing machine comprising cooperable work clamping elements, power operated means for moving one of said elements toward and from the other, electrical means for heating the other of said elements, a switch whereby the energization of said heating means may be controlled, and connections between said switch and the means for moving said clamping element so constructed and arranged as to decrease the supply of heat as said element is moved away from the cooperating presser element.

60. 6. A machine of the class described comprising a bed plate, a die plate cooperable therewith, an electrical heating coil asso-

ciated with said bed plate, a switch in circuit with said coil, manually controllable, power actuated means for moving said die plate toward the bed plate, and means movable in synchronism with said power actuated means for closing said switch. 70

7. A pressing machine comprising a bed plate having an electrical heating coil therein, a die plate movable toward and from said bed plate, a switch in circuit with said coil, 75 a pneumatic motor for moving said die plate toward the bed plate, a pneumatic motor for closing said switch, and manually operable means for admitting fluids to said motors for operating them simultaneously. 80

8. A pressing machine comprising a bed plate having an electrical coil for heating the same, a die plate movable toward and from the bed plate, a switch for controlling the current flow through said coil, a 85 pair of cylinders having pistons therein, means for connecting the pistons to said die plate and the switch respectively, a conduit for pressure fluid having branches delivering into the respective cylinders, and a 90 manually controllable valve for controlling the flow of fluid in said conduit.

9. A machine of the class described comprising a presser element, means for supplying heat thereto at a normal predetermined 95 rate, and means comprising a plurality of relatively movable elements permitting the supply of heat at an abnormal rate thereto and in proportion to the heat removed therefrom by the material operated upon. 100

10. A machine for folding and pressing collar and cuff blanks comprising cooperable work clamping elements, one of said elements having a heat conducting blank engaging surface, means for moving one of said elements toward and from the other, means for supplying heat in predetermined amounts to that one of said elements having the heat conducting blank engaging surface, and automatic means for increasing the 105 amount of heat supplied during each approach of said clamping elements. 110

11. A machine of the class described comprising cooperable work clamping elements, means for moving one of said elements toward and from the other, a heating coil associated with one of said elements, means in circuit with said heating coil for limiting the flow of current therethrough, and means operable in time with the movement of said work clamping elements into cooperative 115 relation for short circuiting said flow limiting means whereby to permit increase of current flow through the heating coil. 120

12. A pressing mechanism comprising a 125 bed plate, an electrical heating coil associated with said bed plate, a die plate movable toward and from said bed plate, a reactance coil in circuit with said heating coil, switch means for short circuiting said 130

reactance coil, and means for simultaneously closing said switch and moving said die plate toward the bed plate.

13. In combination with a machine having a bed plate provided with an electric heating coil and a pneumatically actuated die plate movable toward and from said bed plate, a controlling device for regulating the heating current supplied to said bed plate, said device comprising a support having a pneumatic cylinder mounted thereon, a piston in said cylinder, a reactance coil in circuit with the heating coil of the bed plate, a pair of normally separated contact members so constructed and arranged that when brought into contact the reactance coil is short circuited, and means whereby movement of the piston serves to bring said contact members into engagement.
14. In combination in a press having a frame, an electrically heated work clamping element and a cooperating pneumatically actuated clamping member, a current controller for determining the heat imparted to said heated element comprising a support having means for attaching it to the press frame, a normally open switch mounted thereon and arranged to be connected in circuit with the heating means of the press, a pneumatic cylinder fixed to said support,
- 15 a piston in said cylinder, means whereby movement of the piston serves to close said switch, and means for connecting the cylinder with a source of pressure fluid simultaneously with the actuation of said pneumatically operated clamping member. 35
16. In combination in a press having an electrically heated work clamping element, a cooperating movable clamping member, a pneumatic motor for actuating said movable clamping member, a current controller for determining the heat imparted to said heated element comprising a support having a pneumatic cylinder mounted thereon, a piston movable in said cylinder, spring means 40 for moving said piston in one direction, means for admitting pressure fluid to said cylinder for moving the piston in the opposite direction, a switch, comprising a resiliently supported circuit closer, arranged to be included in the heating circuit for the press, a member carried by the piston and engageable with said circuit closer, upon admission of pressure fluid to the cylinder, whereby to close such circuit and means for 45 simultaneously admitting pressure fluid to the said member and cylinder. 50
17. In combination in a press having an electrically heated work clamping element and a cooperating pneumatically actuated clamping member, a current controller for determining the heat imparted to said heated element comprising a support having means for attaching it to the press frame, a normally open switch mounted thereon and arranged to be connected in circuit with the heating means of the press, a pneumatic cylinder fixed to said support,
- 18 a piston in said cylinder, means whereby movement of the piston serves to close said switch, and means for connecting the cylinder with a source of pressure fluid simultaneously with the actuation of said pneumatically operated clamping member. 55

Signed by me at Troy, New York, this 23rd day of September 1921.

ORVILLE E. COOK.
